Inventor:

Henry Berger

United States Patent Office.

HENRY BERGER, OF NEW YORK, N. Y.

Design No. 3,069, dated June 16, 1868.

DESIGN FOR A CENTRE-PIECE.

The Schedule referred to in these Letters Patent and making part of the same.

TO ALL WHOM IT MAY CONCERN:

Be it known that I, HENRY BERGER, of the city, county, and State of New York, have invented a new and original Design for Centre-Pieces; and I do hereby declare the following to be a full, clear, and exact description thereof, which will enable those skilled in the art to make and use the same, reference being had to the accompanying drawing forming part of this specification.

The drawing represents a face view of this design.

This design consists of central flower A, which is surrounded by a wreath, B. The flower A occupies the centre of a series of concentric circles C, forming a frame for the wreath B. This frame is ornamented by a garland, D.

What I claim as new, and desire to secure by Letters Patent, is—

The design for centre-pieces, herein shown and described.

HENRY BERGER.
